ELECTRICAL RELAY

Arthur E. Dodd, Edgewood, Pa., assignor to The Union Switch & Signal Company, Swissvale, Pa., a corporation of Pennsylvania

Application November 27, 1945, Serial No. 631,160

4 Claims. (Cl. 200—5)

1

My invention relates to electrical relays, and particularly to contact mechanisms for electrical relays.

More particularly, my present invention relates to contact mechanisms for relays of the variety usually referred to as L or "telephone" type relays, and has for an object the provision of a contact mechanism whereby an electrical circuit controlled thereby will become closed during operation of the contact mechanism in one direction only.

Another object of my invention is to provide a contact mechanism including a normally closed and a normally open contact so arranged that the normally closed contact will open after the normally open contact closes during operation of the contact mechanism in one direction, and will subsequently remain open until after the normally open contact opens during operation of the contact mechanism in the opposite direction.

A further object of my invention is to provide a contact mechanism of the type described in which each contact includes a relatively fixed and a relatively movable contact finger and in which the relatively movable contact fingers are connected by a toggle link which causes the normally closed contact to function with a snap action due to the inherent resiliency of the movable contact fingers.

Other objects and characteristic features of my invention will become apparent as the description proceeds.

I shall describe one form of contact mechanism embodying my invention, and shall then point out the novel features thereof in claims.

In the accompanying drawings, Fig. 1 is a view showing in side elevation a relay provided with one form of contact mechanism embodying my invention. Fig. 2 is a top plan view of the relay and contact mechanism shown in Fig. 1. Fig. 3 is a view in side elevation of the relay shown in the preceding views with the parts in the opposite extreme positions from that in which they are shown in the preceding views.

Similar reference characters refer to similar parts in all three views.

Referring to the drawings, the reference character A designates an L or "telephone" type relay which in the form here shown comprises an L-shaped backstrap 1 of magnetizable material having a short leg 1a and a long leg 1b. A magnetizable core 3 is fastened to the short leg 1a of the backstrap 1 by a machine screw 4, and this core extends parallel to the long leg 1b and carries an operating winding 5. Pivotedly mounted

2

at the free or forward end of the long leg 1b of the backstrap 1 is an L-shaped armature 6, the legs 6a and 6b of which are substantially equal in length. The leg 6a of the armature 6 coacts with the free end of the core 3, while the leg 6b in the deenergized position of the armature extends substantially parallel to the long leg 1b of the backstrap 1. As here shown, the leg 6b of the armature 6 is formed with two parallel side portions 6c. The armature 6 is pivotally attached to the backstrap 1 by means of a plate 8 which is fixed to the backstrap 1b by screws 8a, and which projects beyond the free end of the leg 1b. The projecting portion of the plate 8 is provided with two oppositely disposed recesses 9 which receive the two parallel portions 6c of the armature 6 whereby the armature is hinged to the backstrap 1 without trunnions.

The armature 6 actuates contact mechanism embodying my present invention, which contact mechanism in the form here shown comprises four flexible contact fingers 10, 11, 12 and 13 clamped at one end in superposed parallel spaced relation between insulating spacing blocks 14 secured by means of screws 15 to the long leg 1b of the backstrap 1 at the end opposite to the armature 6. The contact finger 10 cooperates with a plate 8b of insulating material attached to the leg 6b of the armature 6, and this finger is so adjusted that it presses against the plate 8b with sufficient force to swing the leg 6a of the armature 6 away from the free end of the core 3 when winding 5 is deenergized. It will be apparent, therefore, that when the winding 5 becomes energized, the resultant upward movement of the insulating plate 8b will cause corresponding upward movement of the contact finger 10. The contact finger 10 carries a low resistance contact button 10a which cooperates with a low resistance contact button 11a provided on the free end of the contact finger 11. This latter finger is so adjusted that when the parts occupy the positions which they occupy when the winding 5 is deenergized, as shown in Fig. 1, the two contact buttons 10a and 11a will be separated by an air gap so that the contact formed thereby will be open, but that when the armature 6 moves to its attracted position in response to energization of the winding 5 as shown in Fig. 3, the resultant upward movement of the contact finger 10 will cause the contact button 10a to move into engagement with the contact button 11a at an intermediate point in the stroke of the armature to thereby close the contact formed by the contact buttons 10a and 11a. A relatively stiff metal stop

16 is clamped between the insulating blocks 14 directly below the contact finger 11, and this stop cooperates with the finger 11 to accurately determine the position in the stroke of the armature at which the contact button 10a will move into or out of engagement with the contact button 11a.

Formed on the free end of the finger 10 is a U-shaped return bend 10b the upper leg 10c of which extends into a V-shaped notch 15a formed in one end of a toggle link 15. The other end of the toggle link 15 is provided with a similar V-shaped notch 15b which receives the free end of the finger 12. The U-shaped return bend 10b is of such length and the parts are so proportioned that when the armature 6 is swung to its released position due to the bias of the finger 10, the end of the toggle link which is connected to the finger 10 will be swung below the plane to which the finger 12 is biased due to its inherent resiliency and the free end of the finger 12 will be moved some distance above this plane. The parts are further so proportioned that when the armature moves toward its attracted position, the resultant upward movement of the finger 10 will cause the end of the toggle link which is connected to the finger 10 to move above the plane of the outer end of the finger 12 at some point in the stroke of the armature after the contact button 10a has moved into engagement with the contact button 11a, whereupon the finger 12 will snap downwardly due to the toggle action of the toggle link to a position in which the free end of the finger 12 is disposed below the plane to which it is biased by its inherent resiliency.

The contact finger 13 is provided at its outer end with a contact button 13a which cooperates with a contact button 12a provided on the finger 12, and is so adjusted that when the parts occupy the position which they occupy when the winding 5 is deenergized, the two contact buttons 12a and 13a will engage each other to form a normally closed contact, but that when the parts occupy the positions which they occupy when the winding 5 is energized, the button 12a will then be moved out of engagement with the button 13a so that the contact formed by the buttons 12a and 13a will then be open. A fixed stop 17 is clamped between two of the insulating blocks 14 directly below the finger 13 to accurately determine the position in the downward stroke of the finger 12 at which the contact formed by the contact buttons 12a and 13a will open, and two other stops 18 and 19 are clamped between two of the blocks 14 on opposite sides of the finger 12 to limit the upper and lower extreme positions of the finger 12.

With the contact mechanism constructed in the manner just described it will be apparent that the two contact fingers 10 and 11 comprise a slow moving normally open type of contact, whereas the two fingers 12 and 13 comprise a quick acting normally closed type of contact. It will also be apparent that when the relay becomes energized, the contact comprising the fingers 10 and 11 will become closed for a brief interval of time before the contact formed by the fingers 12 and 13 becomes opened. It will further be apparent that when the relay becomes deenergized after having been energized, the parts will return to the positions in which they are shown in Fig. 1 due to the inherent resiliency of the movable contact fingers and the above described proportioning of the parts, and that during this movement the contact formed by the contact buttons 10a

and 11a will open before the contact formed by the contact buttons 12a and 13a closes. It follows, therefore, that I have provided a contact mechanism by virtue of which an electrical circuit can be made to become closed during operation of the contact mechanism in one direction only.

One application of such a contact mechanism for railway signaling purposes is illustrated in Fig. 1. As here shown, a bell D with a high capacity electrolytic condenser C shunted across its terminals is connected in series with the two contacts of the contact mechanism in an electrical circuit which is supplied with current from the terminals B and X of a suitable source not shown in the drawing. With the bell connected in this circuit in the manner shown when the relay A picks up, the condenser C will become charged during the interval in which the two contacts are closed while the armature is picking up and will discharge through the bell as soon as the normally closed contact 12a-13a opens. When the relay releases, the bell circuit will remain open and it follows, therefore, that the bell will only ring during the picking up of the relay. This action is frequently desirable in centralized traffic control and remote control circuits and heretofore has required two relays to obtain it.

Although I have herein shown and described contact mechanism embodying my invention applied to only one form of relay, it will be understood that this contact mechanism may readily be applied to other forms of relays. It will also be understood that various changes and modifications in the contact mechanism embodying my invention may be made in accordance with the scope of the appended claims, without departing from the spirit and scope of my invention.

Having thus described my invention, what I claim is:

1. A contact mechanism comprising four superposed contact fingers disposed in parallel spaced relation, two of said fingers being relatively movable and the remaining two fingers being relatively fixed, each said movable finger cooperating with a different one of said fixed fingers to form a switch means, and a toggle link connecting the free ends of said movable fingers, the parts being so proportioned and so adjusted that the inherent resiliency of the one movable finger will cause the switch means including such finger to be normally open and the other switch means to be normally closed and that upon movement of said one movable finger in one direction said normally closed switch means will open with a snap action due to said toggle link but not until after said normally open switch means has closed.

2. A contact mechanism comprising four flexible contact fingers supported at one end in superposed parallel spaced relation, two of said fingers being relatively fixed and the remaining two fingers being relatively movable, each said movable finger cooperating with one of said fixed fingers to form a switch means, a U-shaped return bend on one of said movable fingers, and a toggle link disposed between the free leg of said U-shaped return bend and the free end of the other movable finger, the parts being so proportioned and so arranged that the switch means including said one movable finger will be normally open and the other switch means will be normally closed but that movement of said one finger past the position in which said normally open switch means closes will cause said other switch means to open with a snap action due to

the toggle action caused by the inherent resiliency of the movable fingers.

3. A contact mechanism comprising a first movable contact finger biased by its own resiliency to one position and movable to another position, a first fixed contact finger cooperating with said first movable finger to form a first switch means and so adjusted that said first switch means will be normally open but will become closed in response to movement of said first movable finger toward its other position, a U-shaped return bend formed on the free end of said first movable contact finger, a second movable contact finger, a toggle member connecting said U-shaped return bend with the free end of said second movable finger in such manner that the free end of said second movable finger will be biased to a position above or below that which it tends to assume due to its own resiliency according as said first movable finger occupies its one or its other position, and a second fixed finger cooperating with said second movable finger to form a switch means which is closed or open according as the free end of said second movable finger is above or below the position it tends to assume due to its own resiliency.

4. A contact mechanism comprising a first movable contact finger biased by its own resiliency to one position and movable to another position, a first fixed contact finger cooperating with said first movable finger to form a first switch means and so adjusted that said first switch means will be normally open but will become closed in response to movement of said

first movable finger toward its other position, a U-shaped return bend formed on the free end of said first movable contact finger, a second movable contact finger, a toggle member connecting said U-shaped return bend with the free end of said second movable finger in such manner that the free end of said second movable finger will be biased to a position above or below that which it tends to assume due to its own resiliency according as said first movable finger occupies its one or its other position, and a second fixed finger cooperating with said second movable finger to form a switch means which is closed or open according as the free end of said second movable finger is above or below the position it tends to assume due to its own resiliency, the resiliency of said first movable finger being sufficient to return it to its one position upon being released following its movement to its other position.
